(54) **HOSE, INDIA RUBBER**

(76) Inventor: **Samuel Hunt**

Samuel Kient of Baltimore: Maryland
Letters Patent.

The Schedule referred to in these Letters Patent and making
part of the same containing a description in the words of the said
Samuel Kient himself of his improvement in the mode
of conveying water across seas, ponds, bays, or else where by
means of leather or India Rubber cloth Hose.

To all whom these presents shall come, Be it known that
I Samuel Kient of the City and County of Baltimore and
State of Maryland have invented a new and useful improve-
ment in the mode of conveying water across seas, ponds, bays
or elsewhere, by means of leather or India Rubber cloth Hose,
and that the following is a full and exact description thereof
that is to say, I form a hose in the usual ways of making hose
for fire engines, but with less frequent joints, and of suitable
dimensions and strength, to answer the purpose desired, and to
that end when more strength is required than the best quality
of leather will afford, I wrap the leather hose around with can-
vass, Ropes, bands, of leather, cord, metal, or other substances,
which are to be wound round it in spirals or other manner in
as many turns or thicknesses as may be deemed proper to secure
sufficient strength for the hose or piece of hose required.
The said canvas, ropes or other materials which surround it are
to be in most cases well saturated or covered with linseed-
oileum, elastic, or other suitable substance, and also the leather
hose, and in some instances for a further security from burst-
ing or violent injury to one end the hose is made by forming of
planks, say from two to twenty feet in length, more or less, clamped
together with joints, and the joint confined about it with
legs, each of the lengths are to be connected by fastening pieces
of plank upon the vertical sides of one end of each of the boards,
and projecting say eighteen inches, beyond the end of the boards,

and then connecting to the end of the nail joint, or trunk by means of screws or other pins which shall pass through the outside pieces and into the trunk but not quite through it which pins are to be placed opposite to each other, and to serve as pivots, or points to the trunks that they may be raised or lowered with ease, and conform to, or bed themselves in the bottoms of rivers, ponds &c. in an undulating manner, where the nature of the beds of rivers, ^{etc.} require it, not to prevent sand from entering in the hose from being passed, into the joints, at the bottom. I fasten a piece of sheet lead or copper to the plank of one of the trunks, allowing it to slide freely under or between the hose and the plank and, &c. i.e. upon the other or opposing trunk when rivers which have muddy or soft bottoms are to be crossed. I will draw a channel or furrow in the bottom of the river and then sink the hose within it so that the current or tide shall have no power of action upon it.

What I claim as my invention is improvement in the application of hose, whether constructed in the manner set forth or otherwise not intending to confine myself to any particular dimensions or materials in its construction for the purpose of conveying good and wholesome water for the use of cities, towns and villages &c across rivers, ponds, Bays, creeks, or elsewhere.
